UNITED STATES PATENT OFFICE.

WILLIAM H. MILLER, JOHN E. MILLER, AND WILLIAM H. ORGEL, OF CLEVELAND, OHIO.

COMBINATION-FAUCET.

1,078,939.

Specification of Letters Patent.

Patented Nov. 18, 1913.

Application filed August 3, 1912. Serial No. 713,114.

To all whom it may concern:

Be it known that we, WILLIAM H. MILLER, JOHN E. MILLER, and WILLIAM H. ORGEL, citizens of the United States, residing at 5 Cleveland, in the county of Cuyahoga and State of Ohio, have invented certain new and useful Improvements in Combination-Faucets, of which the following is a specification.

10 This invention relates to a combination faucet constructed and adapted to operate substantially as shown and described and particularly pointed out in the claims.

In the accompanying drawings, Figure 1 15 is a plan view of the faucet, and Fig. 2 is a longitudinal sectional elevation thereof. Fig. 3 is a plan view in section corresponding substantially to line $z-z$, Fig. 2. Fig. 4 is a cross section on a line corresponding 20 substantially to $y-y$, Fig. 2.

The object of the invention as thus shown is to provide a faucet adapted to be variously used but with especial advantage as a drinking faucet in its upturned portion and 25 as an ordinary faucet in its down-turned portion or spout, and it may also be used for both purposes at the same time as noted herein.

The faucet as a whole comprises a body B 30 with a central diaphragm or wall 2 dividing the same horizontally and from which proceed the two delivering spouts 3 and 4, the ordinary spout or portion 3 being shown as curved downwardly after the manner of 35 faucets generally and serving the usual purpose, and the upper portion 4 being curved upwardly on a like curvature and provided with a bowl b at its top. At its opposite or inner end the said body B is cylindrical and 40 screw-threaded about its outside and carries a coupling member C of peculiar and original construction, the said member having an internal thread which screws upon the end of the said body and is provided with 45 a reduced inward extension 5 at its middle having an internal thread for coupling up with a supply pipe, not shown. The said extension 5 is of a considerably reduced diameter compared with the outer portion of 50 said coupling and there is an annular space about the same providing a seat for the spring s which surrounds the said coupling extension 5 and bears against the comparatively free reversible disk-shaped washer D. 55 The said washer has a hole through its center for the passage of the fluid which en-

ters the faucet, but may be of a spider pattern if preferred, and also has, in this instance, an annular depression or groove about its center on one side which serves 60 as a bearing for the rear projection on the valves 6 and 7 as shown. The said valves are preferably of rubber and have reduced rear projections 8 which bear against the said disk in the annular groove thereof and 65 the spring S is in constant sustaining relation against said valves through the said disk D with the function to close either valve when pressure from the valve controlling shaft 9 is relieved. The said valves 70 have flat stems 10 and 12 respectively, which are supported in guide channels at their edges in the wall of the body B as seen in cross section, Fig. 4, and operatively pressed against the shaft 9 through the 75 spring S and disk D. The said shaft 9 has a handle H to control the same and is provided with a central bearing at 13 in the diaphragm or wall 2 of the faucet body and two cam or eccentric portions 14 and 80 15 respectively above and below said bearing and opposite each other relatively on the shaft and in position to engage the said valve stems 10 and 12, so that as the said shaft 9 is rotated, one of said valves will 85 be opened and the other closed, depending upon the direction or degree of rotation. For example, as shown in the drawings, the cam 14 is in action against the valve stem 10 and the valve 7 is closed because the cam 90 15 is on the opposite side from said stem. It should have been noted that valve seats 16 are removably and adjustably screwed into the body of the faucet in advance of the said valves and adapted to seat the same, 95 and said valve seats are provided with passages large enough to afford room for the valve stems 10 and 12 respectively and the flow of water upon opposite sides thereof through the faucet. It follows, therefore, 100 that the free disk D comes on one side of the said valves and the said seats 16 on the opposite side, and the spring S is always in action as to both valves to press the same to their seats. By having disk D free as 105 shown either valve is subject to the closing action of the spring though the other valve be open. The valve seats 16 may be pressed into place and the threads dispensed with.

The fountain cup or bowl b has a hub by 110 which it is screwed upon the extremity of the spout 4 and a check plug 18 is inserted

in the said spout and has a comparatively small orifice or passage so as to serve as a check to the outflow of the water under whatever pressure. We also provide a suitable filtering medium or mesh 20 of wire gauze or other material which will screen and more or less filter and retard the flow of the water, and a porcelain or equivalent overflow plug 22 is shown as inserted in the neck 23 in the center of the bowl and which has an orifice of more or less reduced proportions coöperating with plug 18 and screen 20 in limiting the flow of water at this point whatever the pressure or head.

15 In this connection it may be observed that the flow of the water to spout 4 is limited at its passage 24 through the faucet as compared with the free opening provided beneath for the flow of the water to the spout

20 3. Furthermore, if it be desired to have a constant flow of water to the fountain for drinking or other purposes along with a free use of the faucet proper through spout 3, we can temporarily lock the valve 6 back

25 in open position, or in the position seen in Fig. 2, by means of set screw *d*, which is adapted to bear on stem 10 and lock the same against movement.

The gauze member 20 in the extremity of spout 4 is primarily intended to promote a uniform and even flow of water and its filtering value is secondary to this result. Plug 18 may also be omitted in some cases where the valve passage 24 is of the right size to accommodate the pressure in a given place of use. One or both spouts may be made separate from the body and secured thereto by screw threads or otherwise.

What we claim is:

40 1. A faucet body having delivery spouts and a passage through said faucet corresponding to each spout, a valve for each passage and a free disk shaped member bearing against said valves, a spring bear-

ing against said member and tending to 45 close the valves and a coupling on the faucet body having an annular bearing and seat for said spring.

2. In a faucet, a body having a single intake passage and separate discharge spouts, 50 a plurality of valves and a single valve stem to operate the same, a pressure-equalizing member bearing against said valves and a spring bearing against said member and tending to press said valves to their seats. 55

3. A combination faucet having upturned and downturned spouts respectively, a valve for each spout and a spring pressed member bearing against and tending to close said valves, in combination with a rotatable hand 60 controlled shaft having cams operatively engaging the said valves.

4. A combination faucet having a plurality of passages through the same, a valve for each passage having a stem, a shaft provided with cams adapted to engage said stems, a free rocking member behind said valves and a spring bearing against said member. 65

5. A combination faucet having a dia- 70 phragm lengthwise at its center horizontally, and oppositely directed delivery spouts from opposite sides of said diaphragm at its front, a valve corresponding to each spout having a suitable guide stem at its front and a projection on its rear, a rotatable shaft having oppositely disposed cams 75 engaging said stems, a free rocking member bearing against said projections and a spring bearing against said member. 80

In testimony whereof we affix our signatures in presence of two witnesses.
